CLAIM

I claim the ornamental design for a pallet, as shown and described.

DESCRIPTION

FIG. 1 is a top-front-left perspective view of an embodiment of a pallet showing my new design;

FIG. 2 is a bottom-front-right perspective view thereof;

FIG. 3 is a bottom plan view thereof;

FIG. 4 is a front elevational view thereof; the back elevational view is a mirror image thereof;

FIG. 5 is a left elevational view thereof; the right elevational view is a mirror image thereof; and,

FIG. 6 is a top plan view thereof.
